UNITED STATES PATENT OFFICE.

ELOF H. MEDÉN, OF SHORT HILLS, NEW JERSEY, ASSIGNOR TO AMERICAN GASACCU-MULATOR COMPANY, OF ELIZABETH, NEW JERSEY, A CORPORATION OF NEW JERSEY.

DESIGN FOR A LENS HEAD FOR A TRAFFIC SIGNAL.

Application filed March 23, 1922. Serial No. 1,348. Term of patent 14 years.

To all whom it may concern:

Be it known that I, ELOF H. MEDÉN, a subject of the King of Sweden, residing in Short Hills, county of Union, State of New Jersey, have invented a new, original, and ornamental Design for a Lens Head for a Traffic Signal, of which the following is a specification, reference being had to the accompanying drawing, forming a part thereof.

In the drawing:

Fig. 1 is a view in elevation of a lens head for a traffic signal showing my new design;

Fig. 2 is a similar view taken at an angle of 45° with respect to the position shown in Fig. 1; and

Fig. 3 is a top plan view of the head.

I claim:

The ornamental design for a lens head for a traffic signal, as shown.

In testimony whereof I have hereunto signed my name this 21st day of March, A. D., 1922.

ELOF H. MEDÉN.
